Primary Examiner — T Chase Nelson*Assistant Examiner* — Rachel Wolfe(74) *Attorney, Agent, or Firm* — Justin Lampel(57) **CLAIM**

The ornamental design for a sandglass lamp, as shown and described.

DESCRIPTION

FIG. 1 is a perspective view of a sandglass lamp showing the claimed design;

FIG. 2 is a top plan view thereof;

FIG. 3 is a left side elevational view thereof.

FIG. 4 is a rear elevational view thereof.

FIG. 5 is a right side elevational view thereof.

FIG. 6 is a front elevational view thereof; and,

FIG. 7 is a bottom plan view thereof.

The broken lines illustrate portions of the sandglass lamp that form no part of the claimed design.
